No. 633,386.

Patented Sept. 19, 1899.

W. H. MARLEY.

PACKAGE CARRIER FOR BICYCLES.

(Application filed Oct. 8, 1898.)

(No Model.)

Fig. 1.

Fig. 5.

UNITED STATES PATENT OFFICE.

WILLIAM H. MARLEY, OF PITTSBURG, PENNSYLVANIA.

PACKAGE-CARRIER FOR BICYCLES.

SPECIFICATION forming part of Letters Patent No. 633,386, dated September 19, 1899.

Application filed October 8, 1898. Serial No. 692,486. (No model.)

To all whom it may concern:

Be it known that I, WILLIAM H. MARLEY, a citizen of the United States of America, residing at Pittsburg, in the county of Allegheny and State of Pennsylvania, have invented certain new and useful Improvements in Package-Carriers for Bicycles, of which the following is a specification, reference being had therein to the accompanying drawings.

10 My invention relates to certain new and useful improvements in combined luggage-carriers and support for bicycles.

15 My invention particularly relates to an improvement upon the device as set forth in my application filed January 12, 1898, Serial No. 666,469.

20 The principal features of the invention consist in a table or platform that is supported from two horizontal braces attached to the bicycle-frame and in two movable supporting braces or standards that are adapted to be swung downwardly from the platform or table for supporting a wheel in an upright position.

25 Other novel features of the invention reside in the peculiar construction whereby these supporting-rods are forced outwardly during their downward movement and are drawn inwardly in their upward movement, 30 so that when the same are completely folded they will lie in close engagement with the horizontal braces which support the platform or table.

35 Another novel feature of the invention resides in the mechanism for operating these supporting-rods, which is so arranged as to be within easy reach of the rider and which will operate a peculiarly-constructed yoke to which the supporting braces or standards are 40 pivotally secured.

45 My invention finally consists in the novel combination and arrangement of parts hereinafter more fully and specifically described, and particularly pointed out in the claims hereunto appended.

50 In describing the invention in detail reference is had to the accompanying drawings, forming a part of this specification, and wherein like figures of reference indicate corresponding parts throughout the several views thereof, in which—

Figure 1 is a perspective view showing my

improved carrier and support in position upon a bicycle. Fig. 2 is a front view of a portion of a bicycle, the carrier, and support, and the brake-band in position on the periphery of the tire. 55 Fig. 3 is a side view of a portion of a bicycle, the carrier, and support, also showing in dotted lines the operation of the supporting braces or standards and operating-lever. Fig. 60 4 is a perspective view of the yoke. Fig. 5 is an inverted perspective view of my improved carrier and support. Fig. 6 is a perspective view of the brake-band. Fig. 7 is a perspective view of one of the rods with the 65 elevating-spring mounted thereon, also showing the connecting means for securing or connecting the spring to the underneath face of the platform or table.

The object of my invention is to construct 70 a device of this character which is particularly adapted for the carrying of heavy packages—such as cans of milk, bales of hay, baskets of groceries, and the like—and to accommodate such articles I provide a platform 75 or table 1, which has rigidly affixed to its underneath face by any suitable means the horizontal supporting-rods 2, that converge toward each other at their free end and engage the underneath edge of a collar 3, which 80 is rigidly attached to the upright post 4 of the bicycle-frame. For convenience in placing the collar 3 on the post 4 I preferably make the collar of two sections, which are clamped to the posts and secured together 85 by any suitable means, and in order to hold the two supporting-braces 2 underneath the collar I provide an eyelet on the inner face of one brace, which is engaged by a hook attached to the inner face of the other brace. 90 This hook and eye is not shown upon the drawings, but I secure the same to the braces, as at 5.

For binding the two braces more firmly to the underneath face of the table or platform 95 1 I provide a keeper 7, which may be attached to the underneath face of the table or platform and extend across the braces 2 and may also be used as a binding means for the small standards 8, that are attached to the rear 100 edge of the table or platform and secured in position by bending the lower end thereof at right angles and securing the same to the underneath face of the table or platform by any

suitable means, the ends of the keeper 7 being secured to the underneath face of the table or platform, as shown in Fig. 5. This method of securing the keeper also acts as a binding means for the extensions 8, as referred to above. The standards 8 are used for the purpose of securing to the same a strap or other fastening device which may be passed and tied around the basket or other parcel for holding the same firmly upon the platform or table. I pivotally secure to the horizontal braces 2 by means of the keepers 9 an operating-yoke for the operation of the supporting-standards, which will be hereinafter described.

The operating-yoke consists of an upper bar 10, which is pivotally secured to the keepers 9, as before stated, a lower bar 11, and a series of supporting rods or braces 12, 13, and 14. The lower bar 11 extends a suitable distance outwardly from the supports or braces 12 and 14 and is turned upwardly, as at 15, and has formed integral on its outside stops 16 to arrest the outward movement of the supporting-braces when the device is set up.

In connection with a carrier of this description it is preferable that some sort of support be provided which would serve to hold the wheel or, rather, bicycle in a perfectly upright position while the parcel or package was being secured to the table or platform and also for convenience when it is desired to unload the same, and I provide a pair of supporting standards or braces 18, which are pivotally secured to the upper bar of the yoke, as at 17. The standards have secured to their front face, near their upper end, the keepers 19, which engage the lower bar 11 of the yoke, and, as heretofore stated, the movement of the standards outwardly is arrested by means of the keepers 19 coming in contact with the stops arranged on the converging ends of the bar 11. The yoke and standards are operated by means of the lever 20, which is secured to the yoke by means of the hinged portion 21, which is rigidly secured, as at 22, to the bar 10 and at 23 to the bar 11. The free end of this hinged portion 21 extends outwardly from the bar 11 and is secured to the hinged end of the lever 20, as at 25.

The lever 20 is fulcrumed at its opposite end to an auxiliary lever 26, and one end of this auxiliary lever 26 is pivotally secured, as at 27, to one of the supporting-braces 2, while the opposite or free end thereof is formed into a suitable handle, as at 28, to form a means for readily operating the same.

The outward movement of the standards while descending and the inward movement or, rather, folding movement of the same while being elevated are controlled by means of the rods 29, having their one end secured to the supporting-standards, as at 29', and a portion of their outer end screw-threaded, as at 30. I mount upon the screw-threaded ends of the rods 29 a coil or resistance spring 31, which expands on the downward move-

ment of the standards and retracts upon the upward movement of the standards. The free end of this spring is pivotally secured, as at 32, to the keepers 33, which are secured to the underneath face of the platform or table.

The cross or lower bar 11 of the yoke has operating around the clevis or brake-band 34, which is secured at its upper end to the standards or support 13. I use this brake-band or clevis for the purpose of arresting the movement of the front wheel of a bicycle when the supporting-standards 18 are lowered.

In various forms of bicycles the platform or table may be supported by engaging the fork-crown, though in other machines it may be necessary to secure a suitable clamp 35 at a point directly above the head-crown, upon which the rear end of the table can rest. This construction is, however, of minor detail and will of course depend entirely upon the construction of the wheel to which the carrier and support are attached.

The manner in which the carrier is attached to the bicycle will be readily understood from the foregoing, and I will now describe the movement of the supporting-standards when it is desired to set up the support and fold the same.

Assuming that the supporting-standards are in their folded position, the operator grasps the handle 28 of the auxiliary lever 26 and by lifting upward upon the same and forcing it forward causes the lever 20 to press outwardly, thereby carrying the yoke likewise, and owing to the lower bar of the yoke operating in the keepers formed as the supporting-standards the same will assume a vertical position. As the supporting-standards are moving downward the rods 29, which have the springs 31 mounted thereon and which are attached to the standards, will serve to force the same outwardly from each other, so that by the time they assume their vertical position the lower ends thereof have been extended so as to form a sufficient support in order to hold the bicycle in an upright position, and the lever 26 having described a half-circle in its movement the handle 28 therefor engages the lever 20 and retains the standards in their position.

It will readily be observed that when the reverse movement is given to the lever the spring 31 and the rod 29 will serve to draw the supporting-standards toward each other as they are lifted off the ground and bring the same into close contact with the supporting-braces 2. By this time the supporting-standards have assumed their entirely-folded position, where they are held by reason of the lever 26 being thrown beyond the center of the pivotal point for the lever 20. The handle of the lever 26 is supported in a suitable catch 36, which is provided therefor and which is secured on the inner face of one of the supporting-braces.

As the supporting-standards are forced downwardly into their supporting position

the brake-band or clevis 34 is brought into engagement with the wheel-tire, so as to instantly check the speed of the machine.

In order to construct the lever 20 of one piece and permit the hinging of one end to the hinged portion 21 and the pivotal securing of the opposite end to the lever 26, the bar may be twisted, as at 36, which may be done at any desired point, and thereby obtain a flat portion for its hinged end, the remaining portion of the same being edgewise, so as to work in conjunction with the lever 26.

While the foregoing appears to embody the preferable form of my invention, yet I do not wish to limit myself to this exact construction, as it will be noted that various changes may be made in the details of construction without departing from the general spirit of my invention.

Having thus fully described my invention, what I claim as new, and desire to secure by Letters Patent, is—

1. A bicycle-support and luggage-carrier, consisting of a platform or table, supporting-braces for the same, a yoke pivotally secured

to said braces, standards pivotally secured to said yoke and connected to said platform or support, a brake-band carried by said yoke, a hinged lever connected to said yoke and pivotally secured to an auxiliary lever connected to one of the braces, substantially as shown and described.

2. A combined luggage-carrier and bicycle-support, comprising a platform or table having supporting-braces attached thereto, a yoke pivotally secured to said braces, standards pivotally secured to said yoke, a lever for operating said yoke and standards, and rods carrying resistance or elevating springs connecting the said standards to the platform thereby forming a means for controlling the movement of the standards while being raised or lowered, substantially as shown and described.

In testimony whereof I affix my signature in the presence of two witnesses.

WILLIAM H. MARLEY.
